TETHERED BALL TOY

Floreen I. Evitt, 726 Molino, Long Beach, Calif. 90804

Filed Sept. 9, 1974, Ser. No. 504,339

Term of patent 7 years

Int. Cl. D21—01

U.S. Cl. D34—15 P

FIG. 1.

FIG. 2.

FIG. 3.

FIG. 1 is a perspective view of a tethered ball toy with the tethered ball in an engaged position showing my new design;

FIG. 2 is a top plan view thereof with the tethered ball in an unengaged position; and

FIG. 3 is a side elevational view thereof with portions of the tethered ball omitted for convenience of illustration.

I claim:

The ornamental design for a tethered ball toy, as shown and described.
